UNITED STATES PATENT OFFICE.

GEORGE F. BORKMAN, OF SALT LAKE CITY, UTAH.

LOUD-SPEAKER UNIT.

Application filed February 2, 1927. Serial No. 165,413.

This invention relates to an electromagnetically actuated loud speaker unit and its principal objects are to provide an instrument which shall:

- 5 First. Be highly efficient.
- Second. Have means whereby the magnetic flux density operative upon the armature, may be more nearly proportioned to the characteristics of any particular diaphragm 10 than is ordinarily the case.
- Third. Have the pole pieces arranged for a large area of contact with the permanent magnet.
- Fourth. Lessen to a considerable degree, 15 the liability of "freezing" to the pole pieces.

Fifth. Be simple to assemble, and therefore economical to manufacture.

In attaining these objects, I use preferably a permanent magnet of U-shape with pole 20 pieces mounted along the inside faces of the legs thereof. The pole pieces are preferably of similar shape, and reversed in position, relatively to each other.

The pole pieces consist, each, of a bar with 25 depending flanges along two opposite edges thereof, while on the third edge is a bracket which extends away from the bar and along the flanges, the flanges and bracket being integral with the bar. The outer surface of the 30 bracket and the end face of the flanges adjacent thereto, are preferably in the same plane, and form a surface of contact against the permanent magnet. The spool may be mounted between the bars and between the 35 flanges of the two pole pieces, while the armature, as usual, may be oscillatingly mounted in the sleeve of the spool. Both flanges of each pole piece are bifurcated, for two purposes, (a) to bring the longitudinal center 40 line of the pin which connects the armature to the diaphragm, closer to the center of oscillation of the armature; and (b) to better control the magnetic flux passing through the armature.

45 By making the gap between the flanges of the pole pieces at one end of the armature, greater than the gap at the other end of the armature, the armature is less likely to freeze to the pole pieces.

50 The features of this invention for which the protection of Letters Patent is desired, are collectively grouped in the claims concluding this specification.

In the drawing, which illustrates one embodiment of my invention,

Fig. 1 represents a plan;

Fig. 2, the same, with parts broken away to show a section, principally upon line 2-2, Fig. 3, the spool, however, being in section on the center plane thereof;

60

Fig. 3, an elevation in the direction of arrow 3, Fig. 1;

Fig. 4, a section on line 4-4 Fig. 1;

Fig. 5, a detail, in perspective, of a pole piece, the interior thereof being exposed to 65 view;

Fig. 6, a fragmentary diagram enlarged, showing the relationship between the armature and the pole pieces;

70

Fig. 7, a plan of the armature alone.

Referring to the drawing, 20 indicates the cap, 21 the plate, and 24 the locking ring for clamping the cup and cap together, the diaphragm 25 being interposed, all in accordance with my co-pending application for U. S. Patent, Serial No. 165,412, the filing date of which is even herewith. The plate 21 carries integral placement members consisting of the lugs 26, and the stops 27. The U-shaped permanent magnet 38 rests with one of 80 its U-faces on the upper surface of the cap 21, being positioned in assembling by the stops 27 and the lugs 26, and held between the latter by means of the screws 29 which pass through the lugs 26, through the respective legs of the magnet, and finally, are threaded in the brackets 41 of the pole pieces.

85 The spool 31 with its coil 32, is held between the bars 43 and flanges 45 of the pole pieces. The armature 28 may be eccentrically pivoted at 35 in the sleeve of the spool and be connected to the diaphragm by the duplex pin connection consisting of the primary part 30 and the bent auxiliary part 30¹, 90 as disclosed in my pending application for U. S. patent, filed August 23, 1926, Serial No. 130,920.

95 An important part of the present invention consists in bifurcating the flanges 45 of the pole pieces by cutting the transverse slots 50, defined by the forward flange portions 45¹ and the rearward flange portions 45². This construction is particularly advantageous for use in conjunction with the duplex pin just described, as it enables me to bring the points 100 where the two branches of the pin are connected to the armature, much closer to the center of oscillation, than is the case where the connections are made to the armature outside the outer flange planes of the pole pieces. By thus bringing the lines of action of the 105 pins nearer the center of oscillation of the 110

armature, the lever arms of the armature, which perform the work, are shortened, and the force transmitted by the armature to the diaphragm, correspondingly increased.

5 By referring to Fig. 4, it will be noticed that the pin connections to the armature substantially coincide with the centers of application of the magnetic flux from the pole pieces to the diaphragm. Thus, the power 75 arms and work arms of the armature are substantially equal to each other, which is not the case when the pin connections to the diaphragm lie outside the outer face planes of the pole piece flanges.

10 The other advantage which accrues through the bifurcated arrangement of the pole piece flanges, is the fact that the width of the slots, indicated by the arrows 51, Fig. 5, may be varied, thereby varying the amount 80 of magnetic flux that is concentrated upon 85 the armature. In this way, if a heavy diaphragm is used, a greater force can be concentrated upon it, by making the width of the slot correspond to the result desired. 90

25 Again, if a lighter diaphragm is used, the force operative upon it may be correspondingly lessened.

30 By means of the brackets 41, together with the end faces of the flanges 45, the area of contact between the pole pieces and the permanent magnet 38, is rendered comparatively 95 large, so that the magnetic flux will pass freely from one to the other.

35 The fact that the pin connections from the armature lie inside the outer surfaces of the pole piece flanges, enables me to make the armature purely rectangular in shape without any projecting ears, thereby not only simplifying the manufacture and reducing 100 the cost of production, but actually increasing the power of the armature by reducing the dead load to be moved by the magnetic flux.

40 One of the gaps between the pole pieces, in this instance the one at 52, is made somewhat 105 greater than the other one, in order that the armature in vibrating, shall at no time simultaneously touch two pole pieces.

45 Although my duplex pin connection from the armature to the diaphragm is specifically 110 shown herein, it will be obvious that the present invention can be advantageously used with any ordinary pin connection.

50 As it is old in the art to associate permanent magnets with pole pieces, electromagnet coils, and oscillating armatures, and also, to 115 connect armatures to diaphragms by means of pins, I assert no novelty for the mere association of such elements with one another, but limit my invention to the unique features 120 of the pole pieces as herein disclosed, or their equivalents, and to the unique combinations thereof with the other elements as defined in the claims that presently follow.

55 While a particular embodiment of this in-

vention is herein shown and described, it must be clearly understood that the detailed parts thereof, may or may not, appear in the preferred forms, and also, that the preferred forms may be varied from time to time, depending upon the circumstances and conditions governing and governed by, the development of this invention and the arts to which it is incident, therefore its scope is broadly stated in the claims.

75 Having fully described my invention, what I claim is:

1. A permanent magnet, pole pieces extending from the poles thereof with flanges in mutually overlapping relation, a vibrating 80 armature operatively disposed between said pole pieces, and a bifurcation defined in each of the flanges of the said pole pieces.

2. A permanent magnet, pole pieces extending from the poles thereof, said pole pieces having flanges in cooperative relation, an armature mounted for operation between said flanges, and bifurcations defined in the said flanges where said flanges are operative on 85 said armature.

3. A permanent magnet, pole pieces extending from the poles thereof, said pole pieces having flanges extending towards and in cooperative relation to each other, and an armature mounted for operation between said 95 flanges, the operative effect of said pole pieces on said armature being modified by bifurcations defined in said flanges.

4. A permanent magnet, pole pieces having flanges extending from the poles thereof in 100 cooperative relation to each other, bifurcations defined in said flanges, and an armature mounted between said flanges.

5. A permanent magnet, pole pieces having flanges extending from the poles thereof in 105 cooperative relation to each other, an armature mounted in operative relation to said pole pieces, bifurcations defined in said flanges, said bifurcations being located to 110 modify the effect of the pole pieces on the armature, and a diaphragm connected to said armature.

6. A permanent magnet, pole pieces in contact therewith, said pole pieces having two pairs of flanges extending mutually towards each other, thereby defining gaps between them, and an armature poised so as to have one end thereof positioned in one gap, and the other end thereof positioned in the other gap, one of the said gaps being of greater 115 extent on either side of the center position of the said armature, than the other gap.

7. A permanent magnet, pole pieces in contact therewith, said pole pieces having two pairs of flanges extending mutually towards each other, said flanges being bifurcated, gaps defined between said pole pieces, and an armature poised so as to have one end thereof positioned in one gap, and the other end thereof positioned in the other gap, one of the said 120 125 130

gaps being of greater extent on either side of the center position of the said armature than the other gap.

8. A permanent magnet, pole pieces having bifurcated flanges extending from the poles thereof in cooperative relation to each other, an armature mounted for operation between said pole pieces, a diaphragm operatively positioned, and a connecting member extending from the armature to the diaphragm, the said connecting member being positioned in the space mutually defined by the bifurcated portions of said flanges.

9. A permanent magnet, pole pieces having bifurcated flanges extending from the poles thereof in cooperative relation to each other, an armature mounted for operation between said pole pieces, a diaphragm operatively positioned, and a duplex pin extending from the armature to the diaphragm, the said duplex pin being positioned in the space mutually defined by the bifurcated portions of said flanges.

10. A U-shaped permanent magnet, pole pieces connected to the legs thereof in mutually reversed relation, said pole pieces com-

prising each, a bar with depending flanges, bifurcations defined in said flanges, and an armature poised in the gap between said flanges so as to be influenced by the magnetic flux passing through said bifurcated portions.

11. A source of magnetism, pole pieces arranged to conduct flux thereof, said pole pieces extending mutually toward each other, and an armature operatively mounted between said pole pieces, said pole pieces having each polar extremity thereof bifurcated in a manner to modify the effect of the magnetic flux upon the corresponding extremity of said armature.

12. A source of magnetism, a vibrating armature influenced along its polar extremities by flux from said source, and means for bifurcating the flux at each of the said extremities of the armature.

13. A pole piece comprising a bar, flanges depending from opposite sides of said bar, and transverse slots defined in the said flanges.

In testimony whereof, I sign my name here-
to.

GEORGE F. BORKMAN.
